BOTTLE DRAINER RACK

Frank P. Gutierrez, Van Nuys, Calif. (8332 Sedan Ave., Canoga Park, Calif. 91304)

Filed May 24, 1973, Ser. No. 363,341

Term of patent 14 years

Int. Cl. D7—06

U.S. Cl. D7—71

FIG. 1 is a perspective view of a bottle drainer rack, showing my new design;

FIG. 2 is a rear elevational view thereof;

FIG. 3 is a left elevational view thereof, the broken line showing of the bottles being for illustrative purposes;

FIG. 4 is a top plan view thereof;

FIG. 5 is a bottom plan view thereof; and

FIG. 6 is a front elevational view thereof.

I claim:

The ornamental design for a bottle drainer rack, substantially as shown and described.
